UNITED STATES PATENT OFFICE.

JOHN H. THEISS, OF PARLIN, NEW JERSEY.

DIPPING APPARATUS.

Application filed September 12, 1923. Serial No. 662,180.

This invention relates to apparatus for painting various articles and, more particularly, it relates to apparatus which provides for containing the paint during shipment and also during the painting operation, which provides for holding the article during the dipping or immersing of the article in the paint, and which provides for holding the article during the drying. It is the principal object of the invention to provide an apparatus having the desirable features mentioned. To this major end and also to improve generally on devices of the character indicated the invention consists in the various matters hereinafter described and claimed.

Without restricting the invention thereto it is described with more particular reference to the embodiments illustrated in the accompanying drawings. These embodiments are shown as particularly adapted for, and in use in connection with, the painting of golf balls, but it will be understood that apparatus of the invention is not confined to such particular adaption or use. In the drawings:

Figure 1 is an elevational view of one form of the device, partially vertically sectioned substantially on the line 1—1 of Figure 2, the rest prongs removed in the sectioning being shown, however, by dot-and-dash lines;

Figure 2 is an underside view of the cover of the device shown in Figure 1;

Figure 3 is cross-sectional view of said cover, taken substantially on the line 3—3 of Figure 2;

Figure 4 is a plan view of the auxiliary sleeve of the device shown in Figure 1;

Figure 5 is an elevation of said sleeve with the side wall broken away, but with the article support, removed by the breaking away, shown in dot-and-dash lines;

Figure 6 is an elevation of a somewhat different form of device partially sectioned substantially on the line 6—6 of Figure 7 but with the article support, removed in the sectioning, shown in dot-and-dash lines;

Figure 7 is a plan view of an auxiliary member forming a part of the assembly of Figure 6;

Figure 8 is a diametrical cross-section of said member, and

Figure 9 is a plan view of a cover for

use in connection with the elements shown in Figure 6.

In accordance with the invention, the device presents a container proper for the material, as golf ball enamel, with which the article, as a golf ball, is to be coated, a cover for the container, and means for holding the article during coating and drying, the arrangement being such that the coating and drying operations may be performed without the operator having to touch the article, and without waste of enamel.

Referring for the present to the embodiment illustrated in Figures 1 to 5, the device comprises a container 1 desirably of cylindrical form, an auxiliary member, or sleeve, or container extension 2 open at each end, and a combined cover and article rest 3, the sleeve and cover forming a species of superstructure. The lower end of the sleeve 2 is provided with a plurality of article supports 4, attached to the wall of the sleeve 2 in any suitable manner, as by soldering. Desirably these supports are but three in number, as shown, giving a minimum number of contacts with the article while adequately supporting it. Furthermore the supports are given ends 4^a of minimum area. The cover 3 is similarly provided, preferably upon its closing wall 5, with similar supports 6. As will be understood, the coating elements or supports 4 and 6 are so arranged, and so spaced by the sleeve, as to confine and position the article. The sleeve is given a close friction fit in the container 1, whereby it will remain in position during the dipping operation. The cover is given a similar fit upon the sleeve.

In using the device, a suitable quantity of enamel is placed in the container 1, the sleeve 2 assembled with the container, a golf ball set upon the rests 4, and the cover 3 put on. The device is then inverted, resulting in the immersing of the ball in the enamel. Then the apparatus is again placed upright, whereupon the excess enamel drains from the ball back into the main body of enamel, eliminating any waste. Desirably, in order to hasten the drying, the sleeve and cover, carrying the ball, may be removed from the container after a time, such removal giving opportunity to invert the parts, i. e. stand them upon the wall 5 of the cover, which is desirable as it provides for a run-back of

the enamel, which tends to give a more uniform coating and eliminates the drip, and the sleeve may be removed. If desired, a plurality of covers 3 may be supplied for each container 1, so that while previously coated balls are drying on some of the covers, other balls may be coated, using other covers. It will be understood that the container 1 may be of a size to contain sufficient enamel for coating a plurality of balls.

Referring now to the embodiment shown in Figures 6 to 9, the assembly comprises the container 7, an auxiliary member 8 and a cover 9, the member and cover forming a species of superstructure. The auxiliary member which has a close (e. g. spring) fit in the container 7, is provided with rests or supports 10, located with respect to each other substantially as are the rests 4 or 6, previously mentioned. The cover 9 is provided with the central locating member or contact 11, so positioned with respect to the rests 10, and the article intended to be enameled, as to prevent the article leaving the confine of the rests 10 when the assembly is inverted during immersion. Conveniently, the rests 10 are provided by cutting the sheet metal auxiliary member 8 along lines 30 *a* and *b* leaving *c* as the base of the rest (Figure 7). When the consumer receives the assembly he bends up the rests. If desired, if the container 7 is to be used as a shipping container, a second closure, 12, may be provided, the same being substantially like the auxiliary member 8 except that it is unprovided with slits *a*, *b*. As is obvious, a cover such as the cover 12 may also be supplied and used with the form of the device shown in Figure 1, it fitting in the top of the container 1 in place of the superstructure 2.

In original assembly, the closure 12 closes the container 7, while the auxiliary member 8 merely rests in the cover 9. When the consumer is ready to use the package he removes the cover 9, takes out the closure 12 from the container 7, and the auxiliary member from the cover 9, bends up the rests 10, places the member 8 in place in the container, and applies the cover 9. The use of this type of dipping apparatus will be evident from the previous explanation, it only being necessary to note that in the dipping the enamel reaches the cover 9 through the holes 13 formed by the bending up of the rests 10.

Devices embodying the invention may conveniently be made of sheet metal, giving a convenient, handy and effective combined shipping container and dipping device at low cost. As will be understood, the various joints between the parts, as for example the joint between the container 1 and sleeve 2 and that between the sleeve 2

and cover 3 may be given such bell and taper as is desirable to give a close fit and also facilitate separation of the parts after use.

I claim:

1. In a dipping device, in combination, a container proper for the dipping material and having a discharge opening, a superstructure in container form and having an opening for communication with the opening of said container, and means for locating the article to be dipped wholly within said superstructure whereby the article may be drained, when the container is full, without reversal of said superstructure, such means permitting passage of the dipping material into said superstructure and return of excess material to said container. 70

2. In a dipping device, in combination, a container proper for the dipping material and having a top opening, a superstructure in container form with a closing top and a bottom opening, for assembly with said container, with said openings in communication, and means for locating the article to be dipped wholly within said superstructure whereby the article may be drained, when the container is full, without reversal of said superstructure, such means permitting passage of the dipping material into the 80 superstructure and return of excess material to said container. 90

3. In a dipping device, in combination, a container for the dipping material and having a discharge opening, a superstructure in container form and having an opening for communication with the opening of said container, and means for locating the article to be dipped wholly within said superstructure whereby the article may be drained, when the container is full, without reversal of said superstructure, such means permitting passage of the dipping material into said superstructure, and return of excess material to said container, an element of said 100 means being removable from the superstructure to provide a drying support. 105

4. In a dipping device, in combination, a container proper for the dipping material and having a top opening, a superstructure in container form, with detachable top closure and open bottom, for assembly with said container with said openings in communication, and means for locating the article to be dipped within said superstructure, 115 and permitting passage of the dipping material into said superstructure; elements of said locating means being carried by said detachable top closure, whereby said closure, when detached, may serve as a separate drying support. 120

5. In a dipping device, in combination, a container proper for the dipping material and having a top opening, a superstructure in container form with a closing top and 130

a bottom opening, for assembly with said container with said openings in communication, means for locating the article to be dipped wholly within said superstructure 5 whereby the article may be drained, when the container is full, without reversal of said superstructure, such means permitting passage of the dipping material into the superstructure and return of excess material 10 to said container; said superstructure comprising a sleeve to fit upon said container.

6. In a dipping device, in combination, a container proper for the dipping material and having a top opening, a superstructure 15 in container form, with detachable top closure and open bottom, for assembly with said container with said openings in communication, and means for locating the article to be dipped within said superstructure,

20 and permitting passage of the dipping material into said superstructure; said superstructure comprising a sleeve open at each end and adapted to fit at one end upon said container and provided with elements of said 25 locating means, said detachable top closure fitting upon the other end of said sleeve and other elements of said locating means being carried by said closure.

7. In a dipping device, in combination, a 30 container proper for the dipping material and having a top opening, a superstructure

in container form with a closing top and a bottom opening, for assembly with said container with said openings in communication, means for locating the article to be 35 dipped wholly within said superstructure whereby the article may be drained, when the container is full, without reversal of said superstructure, such means permitting passage of the dipping material into the super- 40 structure and return of excess material to said container; and a cover for said container and presenting elements of said article locating means.

8. In a dipping device, in combination, an 45 open topped container for the dipping material, a sleeve-like member open at both ends and adapted to fit upon the open top end of said container to form an extension thereof, the lower end of said sleeve being 50 provided with article rest means permitting flow of material past the same between the container and sleeve, and a cover adapted to fit upon the open upper end of said sleeve to close the same, and having article rest 55 means, the length of said sleeve and the positioning of said article rest means, fixing such means in relative position for locating the article to be dipped.

In testimony whereof I affix my signature.

JOHN H. THEISS.
